(57) **CLAIM**

The ornamental design for a foam wash mitt, as shown and described.

DESCRIPTION

FIG. 1 is front perspective view of the foam wash mitt incorporating my new design;

FIG. 2 is a front elevation view thereof;

FIG. 3 is a rear elevation view thereof;

FIG. 4 is a left side elevation view thereof, the right side view is identical;

FIG. 5 is a front end elevation view thereof; and,

FIG. 6 is a rear end elevation view thereof.

The broken line shown in FIG. 6 is for illustrative purposes only and forms no part of the claimed design.
